UNITED STATES PATENT OFFICE.

GESNER THEODORE BRANDER, OF CALGARY, ALBERTA, CANADA.

FIREPLACE.

Application filed April 26, 1922. Serial No. 556,697.

To all whom it may concern:

Be it known that I, GESNER THEODORE BRANDER, a subject of the King of Great Britain, and resident of the city of Calgary, 5 in the Province of Alberta and Dominion of Canada, have invented certain new and useful Improvements in Fireplaces, of which the following is a specification.

This invention relates to improvements in 10 fireplaces, and has for its objects to provide a means of conserving the heat generated by the fire in the hearth; to provide a means whereby a supply of cold air may be fed into the hood placed in the fireplace which 15 air will be heated and subsequently radiated through a screen carried by the front of the hood; to provide a means whereby air will be fed from the basement of the house into the hood and also from the rooms of the 20 house; to provide regulating dampers in order to regulate the draft through the hood.

Further objects are to provide a hood which will be located in the open fireplace and provided with a plurality of vertical 25 pipes extending therethrough into a chamber formed in the top of the hood and communicating with the flue, in order to carry off the products of combustion.

Still further objects are to provide an improved open fireplace that is simple in construction, not liable to go out of repair, and generally to adapt the several parts to better perform the functions required of them.

In the drawings:

Figure 1 is a perspective view of an open fireplace equipped with the improved heat saving apparatus.

Figure 2 is a perspective view of the improved device with parts broken away.

Figure 3 is a vertical section through the same.

Figure 4 is a longitudinal section.

Figure 5 is a perspective view of the improved damper plate.

Figure 6 is a perspective view of the improved device taken from the rear thereof.

In the drawings, like characters of reference indicate corresponding parts in all the figures.

Referring to the drawings:

A represents a fireplace of usual construction having the improved device B mounted on top of the fireplace. The improved device consists of a hood or casing 10 having an angular-shaped top 11 in which is formed an angular-shaped chamber 12 communicat-

ing with the fireplace through a plurality of vertical pipes 13 extending through the hood. C indicates the usual grate in the fireplace.

The openings of the pipes 13 in the chamber 12 may be closed or opened by means of two regulating damper plates 14 and 15, which are each provided with elongated slots 16 which are designed to uncover the 65 openings of the pipes 13 when the draft is to be increased. The damper plates 14 and 15 are regulated from the outside of the chimney by means of the two handles 17 and 18.

The outlet flue 19 of the fireplace leads into the chamber 12, and the outlet may be controlled by means of a damper 20 operated by the knob 21. A cold air inlet pipe 22 is provided which is formed with a hopper 75 23 extending to the basement of the house in which the fireplace is located and leading into the outlet flue which is above the damper 20.

A second air inlet is provided by an air 80 duct 25 connected to the hood on the rear wall thereof, as shown at 26, and leading to any suitable place in the wall of the room as at 27. The hood 10, previously described, is formed with an open front wall 85 which is designed to be normally provided with a frame 28 carrying an open-mesh screen 29 through which the air heated in the hood 10 may be suitably radiated into the room.

When a fireplace equipped with this improved device is heated, the products of combustion will rise through the vertical pipes 13 into the chamber 12 and thus through the outlet 19 into the flue. The air 95 supplied to create the required draft will be fed through the hopper from the basement of the house through the pipe 22 and into the flue 19 above the damper 20, whereby the damper 20 will be used to regulate 100 the openings of the pipe 22 and also of the outlet flue 19.

The cold air will be drawn through the pipe 25 and led into the hood 10 underneath the chamber 12 in which it is completely out 105 of contact with the products of combustion which are rising through the pipes 13 in the chamber 12.

The hot products of combustion rising through the pipes 13, and remaining in the 110 chamber 12 for a time which may be regulated by the operation of the damper plates

14 and 15 to vary the openings of the pipes 13, will heat the cold air fed into the hood 10 by the heat radiated through the metallic parts of the hood.

5 The heated air in the hood is then radiated through the screen 29 into the room which is suitably heated. The cold air supplied through the pipe 22 from the basement forms a back draft providing for the necessary draft through the chimney without the same having to be drawn through the fireplace, thereby lessening all chance of the heat being wasted by being drawn through the chimney flue.

15 The draft for the fire in the hearth C may be suitably regulated by the adjustment of the plates 14 and 15 on top of the openings of the vertical pipes 13 through the operating handles or knobs 17 and 18, while 20 the damper 20 in the chimney flue 19 may be operated by the knob 21.

It will be obvious, by means of this improved device, the heat will not be wasted by going out through the chimney flue with 25 the products of combustion, but that the air heated by the fire and the products of combustion, is permanently out of contact from the said products of combustion and unable to escape through the chimney flue 30 19 on account of being housed in the hood 10 which is completely closed from the flue 19. All the air heated is then radiated through the chamber through the screen 29 without any of it being lost through a 35 draft created by the products of combustion escaping through the flue.

As many changes could be made in the above construction and many apparently 40 widely different embodiments of my invention within the scope of the claims, constructed without departing from the spirit or scope thereof, it is intended that all matter contained in the accompanying specifica-

tion and drawings shall be interpreted as 45 illustrative and not in a limiting sense.

What I claim as my invention is:

1. An improved open fireplace comprising, in combination therewith, a hood formed with an open front, a chamber at the top of the hood, a plurality of open pipes 50 extending through the hood into the chamber and opening into the fireplace, an outlet in the chamber, air inlets leading to the hood, and means to regulate the draft through the hood.

2. An improved open fireplace comprising, in combination therewith, a hood formed with an open front and having an angular top, a chamber at the top of the hood, a plurality of pipes extending through 60 the hood into the chamber and opening into the fireplace, means to close the pipes in the chamber, an outlet pipe in the chamber, and air inlets leading to the hood.

3. An improved open fireplace comprising, in combination therewith, a hood formed with an open front and having an angular top, a chamber at the top of the hood, a plurality of pipes extending through 70 the hood into the chamber and opening into the fireplace, a slotted damper plate to close the pipes, and means to operate the plate, an outlet pipe in the chamber, a damper in the outlet, and air inlet pipes leading into the hood.

4. The improved open fireplace claimed in claim 3, in which a frame is provided in the open front of the hood having an open-mesh screen therein.

In witness whereof I have hereunto set 80 my hand in the presence of two witnesses.

GESNER THEODORE BRANDER.

Witnesses:

EVA MYRTLE JOHNSTON,
WALTER ROSS BRANDER.
